(57) **CLAIM**

The ornamental design for a filtration-centrifuge tube for adipose derived stem cells, as shown and described.

DESCRIPTION

FIG. 1 is a rear perspective view of a filtration-centrifuge tube for adipose derived stem cells showing my new design; FIG. 2 is a top elevation view thereof; FIG. 3 is a left side elevation view thereof; FIG. 4 is bottom elevation view thereof; FIG. 5 is a right side elevation view thereof; FIG. 6 is a rear elevation view thereof; and, FIG. 7 is a front elevation view thereof.
